UNITED STATES PATENT OFFICE.

MELCHIOR ZWICKY, OF SPRING TOWNSHIP, BERKS COUNTY, PENNSYLVANIA, AS-
SIGNOR TO TEXTILE MACHINE WORKS, OF WYOMISSING, PENNSYLVANIA, A COR-
PORATION OF PENNSYLVANIA.

CENTER STOP MECHANISM FOR FULL-FASHIONED KNITTING MACHINES.

Application filed August 22, 1924. Serial No. 733,492.

To all whom it may concern:

Be it known that I, MELCHIOR ZWICKY, a citizen of the United States, residing at Spring Township, in the county of Berks 5 and State of Pennsylvania, have invented certain new and useful Improvements in Center Stop Mechanism for Full-Fashioned Knitting Machines, of which the following is a specification.

10 My invention relates to yarn feed mechanism for full-fashioned knitting machines, and particularly to stop mechanism for limiting the travel of the reciprocatively operated yarn-carrier rods commonly employed 15 in such machines.

These yarn-carrier rods are commonly reciprocated through a friction-box mechanism and controlled by screw-actuated stop devices arranged to contact with the ends 20 of the rods or it may be with stop lugs secured to the latter; such known mechanism being indicated in Janssen-Zwicky Patent No. 1,079,915 of Nov. 25, 1913, in connection with which my present invention may be 25 employed, and the latter consisting merely in an improved supplemental stop mechanism intermediately operative upon the yarn-carrier rods to permit of most conveniently effecting desired limitation of the movement 30 of any one or more of them, as fully set forth in connection with the accompanying drawing and clearly defined in the claims.

Fig. 1 is a fragmentary cross-sectional view of a full-fashioned knitting machine 35 showing my improved supplemental stop mechanism applied to the frame thereof in cooperative relation to the intermediately supported yarn-carrier rods; the controlling screw and end stop mechanisms for said rods 40 as commonly employed and indicated in Patent No. 1,079,915 referred to, being omitted as unnecessary to a full understanding of the present improvement.

Fig. 2 is a cross-sectional view on the line 45 2-2 of Fig. 1, looking in the direction of the arrow 2; one stop lever being shown in operative lowered position; and the similar reversely arranged stop lever being shown as only partially raised to the upright position in which the levers are naturally supported when inoperative.

Figs. 3 and 4 are separate perspective views of the stop-carrier head and a stop lever respectively.

Fig. 1 indicates a series of seven yarn-carrier rods 5, 5, 5, an end one 5^a of which may carry the main yarn while any one or more of the others may be used for additional yarn to be fed to certain needles only as determined by means which correspondingly limit their feed movement. The drawing merely indicates midway portions of these rods, engaged in separate guide ways of a supporting bracket 10 of which a series are commonly fixed to the machine frame 60 11; each rod being provided with a suitable thread guide 12 adapted to lay its thread upon sinkers 13. As previously stated description of the operation of the reciprocating and end-stop mechanisms commonly employed and indicated in our prior patent mentioned, is unnecessary to the understanding of my improved supplemental stop mechanism now set forth and which is operative 70 only upon stop lugs 15, 15 secured to the 75 midway portions of the rods for such purpose.

Fixed to the machine frame 11, between two rod-supporting brackets 10 is a special stop-lever bracket 20, having a lever-carrying head 21 which overhangs the series of rods 5 and is spaced above the latter so as to permit free passing of the stop lugs 15. This head is formed with supporting ears 21^a, 21^b for a pivot axle 22 which extends 80 crosswise of the rods 5 midway of the width of the head; and upon this axle is pivoted a series of stop-levers 25, 25, 25 for the several yarn-carrier rods 5. Each of these levers is L-shaped as shown, having a pivot member 90 apertured for mounting upon the pivot axle 22 and a right-angled stop member 25^a adapted to swing into contact with either side of said head and to depend below the latter so as to be engaged by a stop lug 15 on 95 the corresponding rod 5 for stopping the movement of the latter; said depending portion being provided with an adjustable contact 25^b as indicated, to permit of accurately regulating such stoppage, and a handle 25^c 100 being provided for conveniently operating each lever.

Each of the stop levers 25 is thus adapted to be swung reversely upon the axle 22 so as to cooperate with a stop lug 15 secured to 105 the corresponding rod 5 either on one side or other of the stop lever head as may be required; it being understood that the loca-

tion of each stop lug 15 on its rod affects the movement of the latter in one direction only without affecting the limitation to its reverse movement provided for by the usual end-stop mechanism; and that any selected rod may be utilized for a desired purpose as found preferable.

What I claim is:—

1. In a full fashioned knitting machine having a yarn feed mechanism comprising a series of reciprocatively operated yarn carrier rods; an intermediate stop mechanism for said rods comprising stop lugs intermediate secured thereto, a fixed stop-lever bracket having a stop-carrier head spacedly overhanging said series of rods and provided with a pivot axle extending transversely of the latter, and a series of stop levers pivotally mounted on said axle to severally swing thereon into or out of lug-engaging position.
2. In a full fashioned knitting machine having a yarn feed mechanism comprising a series of reciprocatively operated yarn carrier rods; an intermediate stop mechanism for said rods comprising stop lugs intermediate secured thereto, a fixed stop-lever

bracket having a stop-carrier head spacedly overhanging said series of rods and provided with a pivot axle extending transversely of the latter, and a series of stop levers pivotally mounted on said axle to severally swing thereon into or out of lug-engaging position, on one or other side of said overhanging head.

3. In a full fashioned knitting machine having a yarn feed mechanism comprising a series of reciprocatively operated yarn carrier rods; an intermediate stop mechanism for said rods comprising stop lugs intermediate secured thereto, a fixed stop-lever bracket having a stop-carrier head spacedly overhanging said series of rods and provided with a pivot axle extending transversely of the latter midway of the width of the head, and a series of L-shaped stop levers pivotally mounted on said axle to severally swing their stop members into contact with either side of said head; the extremities of said contacted stop members depending below the latter to engage said lugs.

In testimony whereof I affix my signature.

MELCHIOR ZWICKY.
